GRAVITY RETURN SYSTEM

Application filed October 11, 1926. Serial No. 140,834.

My invention relates to a system for entraining liquids, such as water, by means of gas or vapor and it has for its object to provide apparatus of the character designated which may be more readily installed and maintained than similar devices now in use and which shall furthermore be highly effective to perform the desired functions under a wide variety of operating conditions.

More specifically, my invention relates to a modified and improved form of receiver for use in connection with the well-known Holly gravity return system (one form of which is described in Gebhardt's Steam Power Plant Engineering, New York, 1925, at pages 703, 704) and to a system of piping to said receiver whereby condensate drips may be efficiently recovered from pressure zones of slightly different pressures.

In the accompanying drawing, I show in Fig. 1 a diagrammatic view of a Holly gravity return system embodying a receiver and receiver piping constructed in accordance with my invention; Fig. 2 is an enlarged sectional view of the receiver indicated in Fig. 1 and Figs. 3 and 4 are enlarged sectional views of modified types of entraining nozzles adapted for use in the receiver of Figs. 1 and 2.

The Holly system, briefly speaking, comprises a receiver, placed at a low level, such that the high pressure drips flow thereto by gravity. These drips are carried upward to a discharge chamber provided at a sufficient altitude above the boilers to permit a column of water of considerable height between the same and the boiler. Within this discharge chamber, the air and steam separate from the water content which returns to the boiler, the air and vapor being withdrawn through a vent pipe as to a heater, as is well known in the art.

In the past, the receiver construction usually employed had joints or piping at the

bottom of the receiver, and due to the fact that these devices are frequently placed in pits or other depressed positions, they are inaccessible for the purposes of renewals or repairs and are subject to leakage or corrosion from without.

In accordance with the present invention, I mount the receiver at a suitable low point for the collection of the high pressure drips, and I tap the riser through the upper side thereof, the said riser terminating within the receiver in a U-shaped or other return bend entraining nozzle, open at one end, and provided with fluid admitting perforations on one side thereof toward the bottom.

By this means, the entrainer may be readily connected or disconnected, is not subject to corrosion or breakage, and has no inaccessible parts.

If it be attempted to collect drips from zones of slightly different pressure, such, for example, as the ends of a long run of steam pipe wherein considerable pressure drop takes place, it will be found that with simple connections to the Holly receiver, there will either be wastage of steam at the high pressure end or insufficient removal of drip from the low pressure end. Under these conditions I may insert a trap or U-tube in the piping system from the high pressure zone to the receiver such that a water column is opposed to the flow of drip from said high pressure end. I accordingly set up a slight back pressure, due to the unbalanced water column in said U-tube, this back pressure being sufficient to eliminate the effect of the excess pressure in the steam pipe. By this means I am enabled to properly drain various zones of slightly different high pressure to a common receiver, the relative rates of draining being rendered independent of the various high pressures. As an optimum condition, all of the venting steam should be drawn from the drainage point of lowest pressure, since this steam has, in general, a

higher moisture content than that drawn from higher pressure points nearer the boiler. Under these conditions, the drainage from said higher pressure points through 5 said U-tubes is solely water, all gases and vapors being held back by the entrapping action of the U-tubes.

In the accompanying drawings is shown 10 a boiler 6 delivering steam by a main 7, 8, to devices where it is to be used, such as a steam chest 9, and other devices (not shown). The purpose of the present invention is to provide for the automatic return to the boiler 6 of the condensed water from the main 7, 8, 15 and from the devices drawing steam therefrom. For this purpose the steam chest 9 is connected by a drip line 13 to a Holly receiver 10 where the drip water collects. Here the drip water collects in the bottom, first filling 20 a depression 24. Accompanying the drip water, and forming from it by the reduction in pressure at this point remote from the boiler, is considerable steam. The steam lies above the water in the receiver 10 and escapes 25 at the top through the upper open end 23 of a U shaped discharge member 17'. As it escapes, it entrains the drip water through one or more perforations 23' and as it flows around the bottom 22 of the U, the water is 30 carried along with it out the riser line 16 to a discharge chamber or separator 17. The separator 17 is located well above the boiler 6, so that the water separated out in the separator 17 forms a column of considerable 35 height in the return line 18 leading to the boiler 6. As a result, the effective pressure on the riser line 16 is less than that on the main 8 by the weight of the water column in the return line 18, thus providing for a difference in 40 pressure which causes the escape of steam through the upper end 23 and the riser line 16. The air and uncondensed vapors leaving the separator 17 escape through a line 20 to a point where their heat can be usefully employed, as a feed-water heater 21.

In addition to the drip line 13, there may be other drip lines 11 and 12, coming, if desired, from points where the steam pressure is different. For enabling these drip lines to 50 all feed into a single Holly receiver 10 there may be interposed in each a U leg 14 or 15 of such length as to provide a column of trapped water sufficient to partially or wholly equalize any difference in pressure from any 55 other drip line. These legs 14 and 15 may be provided with check valve 15' at the bottom to prevent surging of the water.

The discharge member 17' is internally threaded at the top to receive the lower end 60 of the riser line 16, and is externally threaded to fit the threaded opening in the top of the Holly receiver through which it is inserted, thus providing a unitary device which is easily removable, as for cleaning the receiver 65 10. It is often found advisable to have the

total area of the entraining openings 23' one-third to one-half of the area of the opening 23 to preserve the best rate of flow of steam and water.

Referring to the form of my invention shown in Fig. 3, which is particularly adapted for extremely high pressure work, a flanged thimble 30 is expanded within an opening in the wall of the receiver 10 and it is furthermore welded in places as indicated at 31. A hollow frustro-conical member 32 is seated upon the member 30, its major base resting thereupon, and the member 32 is flanged at both its upper and lower ends for attachment to the member 30 and to riser line 33. A hollow tubular member 34 has its open upper end 35 joined to the interior of the member 32 as by welding as indicated at 36 and has its lower end closed except for fluid entraining orifices such as shown at 37-37. A septum 38 is fastened to the inner surface of the wall 34 adjacent the upper end thereof and projects downwardly therein nearly to the lower end, dividing the space within the member 34 into two separate passages 39 and 40, as indicated. Adjacent the upper end of the passage 40 a large orifice 41 for the entry of air and gas is provided.

Referring to Fig. 4, I show still another form of entraining nozzle which is symmetrical in form and which I have found well adapted to perform the desired function. The member 25 is adapted to be screwed into the wall of the receiver 10 and has a centrally threaded orifice for the receipt of the riser line 16. A depending flange 26 defines a central passage from the riser line 16 to a point adjacent the bottom of a casing 27, also depending from the member 25 and closed at its lower end except for small fluid entraining orifices 28-28. The casing 27 further contains air and vapor admitting orifices 29-29 adjacent its upper end.

In the structure shown in Figure 3 the riser line leading to the separator is shown 110 at 33. Into this the steam in the Holly receiver 10 enters by the opening 41, flowing first downward past the openings 37 where it entrains water, then around the bend 37 and up the riser line 31.

The structure shown in Figure 4 is adapted to be screwed into a Holly receiver 10, so that the steam leaving by the riser line 16 enters through large openings 29, passes downward outside the flange 26 entraining water through the smaller openings 28 and then upward through the riser line 16.

While I have described my invention in a plurality of modifications, it will be obvious to those skilled in the art that it is not limited to such modifications and I desire, therefore, that only such limitations be placed thereupon as are imposed by the prior art or specifically pointed out in the appended claims.

What I claim is:

1. In a device for entraining liquid by a gas or vapor, the combination with a container, of means for supplying thereto said liquid and said gas or vapor, a hollow member mounted within said receiver in a vertical position and provided with a passage therein extending downwardly, laterally and upwardly and having relatively free communication with the interior of said container adjacent the upper portion thereof, said member being provided with lateral perforations therein adjacent the lower end thereof, and means tending to produce and maintain a lower pressure in said projecting member than within the interior of said receiver. 70
2. In a device for entraining a liquid by a gas or vapor, the combination with a closed container, of means for supplying to the interior thereof said liquid and said gas or vapor, a suction tube projecting through the top of said receiver and downwardly into close proximity to the bottom thereof, thence laterally and upwardly into proximity to the top thereof, terminating in a large gas and vapor admitting orifice, said upwardly-extending portion further being provided with a plurality of small liquid-admitting lateral orifices. 75
3. The combination with a receiver for a Holly gravity system of a suction tube projecting through the top thereof, downwardly into proximity to the bottom thereof, thence laterally and upwardly into proximity to the top thereof and terminating in an open end, said upwardly projecting portion being provided with a plurality of liquid admitting perforations. 80
4. The combination with a receiver for a Holly gravity system of a suction tube projecting through the top thereof, downwardly into proximity to the bottom thereof, thence laterally and upwardly into proximity to the top thereof and terminating in an open end, said upwardly projecting portion being provided with a plurality of liquid-admitting perforations and said laterally extending portion being provided with at least one liquid-admitting perforation. 85
5. A receiver for a Holly gravity system comprising a horizontally disposed cylindrical tank provided with a drainage depression in the bottom thereof, a suction tube projecting through the top thereof and downwardly into said depression, thence laterally and upwardly above the normal fluid level, terminating in a large gas and vapor admitting orifice, said upwardly projecting portion being provided with a plurality of small fluid-admitting orifices and said laterally projecting portion being provided with at least one fluid-admitting orifice adapted to withdraw fluid from said depression. 90
6. In a collecting system for condensate drips, the combination with a boiler and a receiver adapted to collect drips from two zones of differing higher pressures, of a direct connection from said receiver to the zone of lower pressure and a connection, including a U-tube having two legs above the receiver, from said receiver to said zone of higher pressure, whereby an opposing hydrostatic pressure is set up in said U-tube equivalent to the difference of pressure between said two zones. 95
7. In a collecting system for condensate drips, the combination with a boiler and a receiver adapted to collect drips from two zones of differing higher pressures, of a direct connection from said receiver to the zone of lower pressure and a connection, including a U-tube having two legs above the receiver having a check valve at the bottom thereof, from said receiver to the zone of higher pressure. 100
8. In a collecting system for condensate drips, the combination with a boiler and a receiver adapted to collect drips from two zones of differing higher pressures, of a direct connection from said receiver to said zone of lower pressure and a connection from said receiver to said zone of higher pressure including means above the receiver for accumulating hydrostatic back pressure for compensating for the excess of pressure therein, whereby the rates of drip collection from said two zones are rendered independent of the differing pressures therein. 105
9. In a collecting system for condensate drips, the combination with a boiler and receiver adapted to collect drips from a plurality of zones of differing higher pressures, of means for developing back pressures proportional to the excess of pressure in each zone, whereby the rates of drip collection from the respective zones are rendered independent of the differing pressures therein. 110
10. In a collecting system for condensate drips, the combination with a boiler and receiver adapted to collect drips from a plurality of zones of differing higher pressures, of means for developing back pressure proportional to the excess of pressure in each zone over said predetermined pressure, whereby substantially all venting steam and gases are drawn from the zone of lowest pressure and only liquids are drawn from the zones of higher pressure. 115
11. In an entraining system for high pressure drips, the combination with a receiver member, of a flange member mounted in the upper wall thereof, a hollow frustro-conical member having its larger base seated upon said flange member and flanged at its upper and lower ends respectively for attachment to said flange member and to a conduit, a tubular member mounted within said frustro-conical member and projecting downwardly into said receiver, said tubular member being open at its upper end and closed at its 120
- 125
- 130

lower end except for a relatively small entraining opening, a diaphragm extending downwardly within said tubular member and defining a fluid passage from the upper end thereof to a point adjacent the bottom thereof, and thence upwardly to a point adjacent the upper end thereof and a relatively large orifice in said tubular member opening into said fluid passage adjacent said last named point.

10 In testimony whereof, I have hereunto subscribed my name this 5th day of October, 1926.
